(57) **CLAIM**

The ornamental design for a tool handle, as shown and described.

DESCRIPTION

FIG. 1 is a front perspective view of the tool handle. FIG. 2 is a first side elevation view of the design of FIG. 1. FIG. 3 is a second side elevation view of the design of FIG. 1. FIG. 4 is a third side elevation view of the design of FIG. 1. FIG. 5 is a fourth side elevation view of the design of FIG. 1. FIG. 6 is a bottom view of the design of FIG. 1; and, FIG. 7 is a top view of the design of FIG. 1. The broken lines in the drawings illustrate environmental structure and form no part of the claimed design.

1 Claim, 4 Drawing Sheets

FIG. 2

FIG. 3
